UNITED STATES PATENT OFFICE.

EMIL GEORGE HESS AND WILLIAM HESS, OF WEST TORONTO JUNCTION,
CANADA, ASSIGNORS TO ALICE GRACE HESS, OF SAME PLACE.

DESIGN FOR A KNOB OR PULL.

SPECIFICATION forming part of Design No. 21,196, dated December 1, 1891.

Application filed April 23, 1891. Serial No. 390,170. Term of patent 14 years.

To all whom it may concern:

Be it known that we, EMIL GEORGE HESS and WILLIAM HESS, both of the town of West Toronto Junction, in the county of York and Province of Ontario, Canada, have invented and produced a new and original Design for Knobs or Pulls, of which the following is a specification.

In the accompanying drawings, Figure 1 is a face view of the knob embodying our design, and Fig. 2 is a perspective view.

The general form of our design is that of a knob having an approximately-convex pe-

riphery with a concave front face, with a series of radiating lines extending from the central portion of the concave face out to and over the periphery of the knob.

Having thus described our invention, what we claim is—

The design for knobs or pulls herein shown and described.

EMIL GEORGE HESS.
WILLIAM HESS.
